CIGARETTE VENDING MACHINE

Robert L. McChristian, Miami, Fla.

Application September 12, 1939, Serial No. 294,556

11 Claims.

(Cl. 312—86)

The invention relates to an article dispensing machine and more especially to a coin controlled vending machine.

The primary object of the invention is the provision of a machine of this character, wherein unpackaged or loose cigarettes will be automatically ejected or delivered from the machine and optionally lighted concurrently with delivery in single order of said cigarettes, the machine being controlled for its automatic operation by the deposit of a coin, token or the like of a determined denomination in the machine.

Another object of the invention is the provision of a machine of this character, wherein different grades or products can be dispensed thereby and in single order, the products being unpackaged or loose for single order delivery thereof.

A further object of the invention is the provision of a machine of this character, wherein the loose cigarettes are protected for eliminating possibility of conflagration in event that when the cigarette to be delivered is automatically lighted concurrently with delivery thereof but fails in making such delivery, the shielding of the undelivered cigarette during the delivery of a lighted cigarette from the machine being novel and assures perfect safety against fire during the working of the machine or when the same is inactive.

A still further object of the invention is the provision of a machine of this character, wherein the construction thereof in its entirety is novel and is positive in the working thereof, the cigarettes being ejected or delivered from the machine are subjected to an air flow under pressure to free the cigarette from dust or foreign matter so that the delivered cigarette will be cleaned automatically when acquired by a person or user of the machine, the cigarette when being lighted is also subjected to the air blast to assure full lighting of such cigarette concurrently with the delivery thereof from the machine.

A still further object of the invention is the provision of a machine of this character, wherein an operator is relieved of manual labor in that the cigarettes loose within the machine will be automatically handled for the ejecting in single order of such cigarettes either lighted or unlighted at the option of the user of the machine.

A still further object of the invention is the provision of a machine of this character, which is comparatively simple in construction, thoroughly reliable and efficient in operation, coin controlled, automatic in the working thereof, portable, and

comparatively inexpensive to manufacture and install.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a vertical sectional view through a vending machine constructed in accordance with the invention.

Figure 2 is a view similar to Figure 1 looking toward the opposite side of the machine.

Figure 3 is a fragmentary sectional view taken on the line 3—3 of Figure 2 looking in the direction of the arrows.

Figure 4 is an enlarged fragmentary sectional view taken on the line 4—4 of Figure 1 looking in the direction of the arrows.

Figure 5 is an enlarged plan view showing the clutch and control thereof with adjuncts.

Figure 6 is a fragmentary elevation partly in section showing steps in the movement of the clutch through the action of a cam blade.

Figure 7 is a plan view of the ejector for single delivery of the cigarettes from the magazine within the machine.

Figure 8 is a fragmentary detail plan view of the commutator type switch employed in the machine.

Similar reference characters indicate corresponding parts throughout the several views in the drawings.

Referring to the drawings in detail, the machine constituting the present invention comprises a casing, a portion thereof being indicated generally at A, and may be of the desired size and shape in accordance with the requirements for the storing of one or any number of grades or brands of smokers' products, such as cigarettes, cigars or the like, preferably cigarettes unpackaged and loose for vending of the same in single order.

This casing A has rising from its enlarged lower portion 10 a perpendicularly arranged columnar upper portion 11 while within the lower portion 10 is disposed superposed with respect to the bottom 12 of said casing a horizontally arranged flooring or supporting bed 13 dividing the said portion 10 into upper and lower compartments 14 and 15, respectively.

Fixed to the flooring bed 13 is a perpendicularly arranged bracket 16 having built therewith at the

upper portion of the same a relatively narrow magazine 17 which is vertically carried into the upper columnar portion 11. This magazine is of a size to accommodate stacked cigarettes 18 unpackaged and loosely confined superimposed with relation to each other within said magazine. The capacity of the magazine 17 may be varied for accommodating a required number of cigarettes 18, these being admitted to the said magazine 17 through the open upper end thereof, the casing A being equipped with a top door 19 so that access may be had to the columnar portion 11 for the filling of said magazine 17 in the charging thereof with loose cigarettes 18.

15 At or close to the lower end of the magazine is a laterally extending guide ledge 20 for slidably supporting an ejector 21 having a receiving and delivering pocket 22 for registering with the magazine 17 when in receiving position for a 20 lowermost cigarette 18 of the stack within the magazine 17. The ejector 21 has clearance through suitable openings in opposite side walls of the magazine 17 for the travel of said ejector to receiving and delivering positions. The delivering position of the ejector 21 is when the same has moved to bring the pocket 22 laterally to one side of the magazine 17 out of registration therewith. The pocket 22 in the ejector 21 opens 25 upwardly and downwardly therethrough, the cigarette being accommodated therein enters through the uppermost opening while the delivery of said cigarette from the pocket is had through the lower opening.

30 The opposite side walls of the pocket 22 in the 35 ejector effect closures for the clearances for the latter in the side walls of the magazine 17. The ledge 20 closes the pocket 22 at the lowermost open portion thereof when said pocket registers with the magazine 17 while this ejector 21 is built 40 at one side of the pocket 22 therein with a cut-off area 23 for the magazine 17 to restrict reception of more than a single cigarette 18 in the pocket 22 from the said magazine 17 during the working of the ejector 21.

45 Provided at the front of the column or portion 11 is a delivery mouth piece 24 through which is projected the cigarette 18 for delivery from the machine in a manner presently described.

50 At one side of the bracket 16 and journaled thereon is a driven gear 25 meshing with a pinion 26 loose upon a driving shaft 27 suitably journaled at 28 which has worm screw and worm gear connections 29 with the power shaft of an 55 electric motor 30, being fixedly arranged within the compartment 15 interiorly of the casing A. The shaft 27 has keyed or splined thereon a tripping sleeve 31 which with the pinion 26 has companion clutch formations 32 so that when 60 the sleeve 31 is shifted in one direction the pinion 26 will be made fast on the shaft 27 for rotation therewith and by movement of said sleeve 31 in a reverse direction the pinion 26 becomes loose on said shaft 27. When the pinion 26 becomes fast on the shaft 27, power from the motor 30 is transmitted to the gear 25 for the driving 65 of the same.

Carried by the bracket 16 is a guide 33 for an actuator slide 34 being of substantially upset U 70 form providing the arms 35 and 36, respectively. The arm 35 slidably engages in the guide 33 and this slide 34 has formed therein an elongated perpendicularly disposed slot 37 accommodating a wrist pin 38 eccentrically fixed to the gear 75 25 so that on rotation of the latter the said slide

will be reciprocated thereby. The slide 34 is formed with an ear 39 having connection at 40 with a head block 41 provided with a rest lip 42 coactive with a rest lip 43 joined with the mouth piece 24, these lips being adapted to accommodate the cigarettes 18 when dropped from the pocket 22 in the ejector 21, the latter receiving the said cigarette at the lowermost portion of the stack within the magazine 17 and thus when the slide 34 is moved in one direction, the single cigarette accommodated upon the lips 42 and 43 will be projected through the mouth piece 24 for the ejecting of said cigarette from the machine.

Working through the front of the casing A is 15 a push or operating bar 44, its outer end without the machine casing A being fitted with a hand knob 45 while the inner opposite end is formed with a twisted cam acting terminal 46, the cam face 47 thereof being engageable with a stationary guide pin 48 rising from the bed 13 in the path of said terminal and is perpendicularly set. This terminal is in the form of a fork 49 for straddling the driving shaft 27 and such terminal acts upon the sleeve 31 on the pushing inwardly 25 of the bar 44 for the shifting of said sleeve to clutching position with the pinion 26. Built in the casing A is a coin slot 50 of a size for accommodating a predetermined denomination of coin, token or the like 51 and this chute 50 opens 30 outwardly of the machine for the hand introduction therewith of the coin, token or the like. In association with the coin chute 50 is a coin actuated mechanism of any approved construction for controlling the bar 44 and in this instance 35 a locking trigger 52 is released by the coin 51 from locking engagement with a keeper 53 on the bar 44 so that said bar can be manually pushed for the automatic operation of the machine. The coin 51, after releasing the trigger 52 from the 40 bar 44, is deposited within the machine.

Above the ledge 20 on the magazine 17 are formed bearings 54 for the pintle 55 of a hinge 56 connected with the ejector 21 while associated with the pintle 55 is a link 57, which is also connected with a cam acting trigger 58 pivoted at 59 to the under side of the bar 44, the link being cleared through the bar 44 at 60. This trigger 58 at its toe end 61 engages in a stationary yoke 62 rising from the bed 13 and of substantially inverted U form. The bar 44 is urged outwardly 50 of the casing A by the action of a coiled spring 63 while the link at its connection with the pintle 55 has associated therewith a coiled retractile spring 64 for assisting in the return of the 55 ejector 21 to normal position, the spring 63 being for the purpose of returning the bar 44 to a normal position after being pushed upon by a user of the machine. The hinge 56 moves the ejector 21 and this is had through the link 57 60 and the trigger 58 coacting with the yoke 62 when the bar 44 is moved.

Included in the electric motor circuit, its current wires being indicated at 65, is a toggle switch 66 controlling the starting and stopping of said 65 motor 30. This toggle switch 66 has operative connection with an annular flange 67 on the sleeve 31 so that on movement of said sleeve to clutching position with the pinion 26 the switch 66 will be moved to circuit closing position and thus the motor 30 started. On reverse movement of the sleeve 31 the switch 66 is moved to open position for the stopping of the motor 30.

Arranged with the motor 30 is an air blower 75

or pump 68, its air flow lead 69 includes the telescopically interfitted units 70 and 71, respectively, the latter being a part of the head block 41 while the former is stationarily held upon the bracket 16, the telescopic arrangement of these units being necessary due to the fact that the slide 34 shifts the head block 41 and in association with the said unit 70 for intersecting the said lead 69 is a flow control valve 72 engaged by the arm 36 for operation thereby through its cam acting edge 73 and in this manner the air flow through the lead 69 is controlled, the air flow being had through the head block 41 for discharge at 74 onto a cigarette accommodated in the lip 42 for the cleaning of such cigarette and also for assuring the automatic electric lighting of such cigarette in a manner presently described.

About the air discharge 74 and fitting the block 41 in confronting relation to the end of the cigarette 18 when accommodated in the lip 42 on said block 41 is an electric lighter 75 involving the usual resistance coil and this lighter is in an electric circuit, the current wires thereof being indicated at 76, and such circuit has therein a transformer 77 as well as a mechanically operated switch 78, the latter being controlled by a striker 79 on the bar 44 which striker is in the path of the opening and closing arm of the switch 78. Thus when the switch 78 is closed the lighter 75 operates for the lighting of the end next thereto of the cigarette 18 at the time of ejecting the said cigarettes singly through the mouth piece 24 so that such automatically lighted cigarette can be acquired by the operator of the machine. The head 41 in the movement of the slide 34 brings contact of the cigarette 18 with the lighter 75 and when the latter is aglow the said cigarette will be automatically lighted.

Fixed to the journal 80 for the gear 25 is a commutator-like rotary switch 81 which is included in the circuit for the lighter 75 and having the wires 76, the contacts and the wiper of this switch 81 being indicated at 82 and 83, respectively. The wiper 83 being of a double brush or arm type and the purpose of the said switch is for the timing of the lighter action 75 when the switch 78 is closed by the striker 79 on the pushing of the bar 44 inwardly and having the latter held in this position with a striker 79 at a point for retaining the said switch 78 closed and in this way a cigarette 18 will be lighted properly during the cycle of ejecting operation of the machine for the delivery of said lighted cigarette therefrom. It is, of course, understood that when the bar 44 is pushed inwardly for the starting of the machine it momentarily closes the switch 78 providing the said bar is relieved of pressure exerted by an operator of the machine on the instant of completion of the inward stroke of said bar and in this a cigarette 18 will be ejected from the machine but not lighted, being required that the said bar 44 be held pushed inwardly so that through the timing action of the commutator-like switch 81 the lighter 75 will operate for effecting the lighting of the cigarette during the ejecting period of operation of the machine. The ejecting period of operation of the machine requires a complete rotation of the commutator-like switch 81. The period of operation of the lighter 75 when the switch 78 is maintained in a closed position is controlled by the extent of the contacts 82 of said switch 81 for the successful and com-

plete lighting of the cigarette by the lighter 75.

Loose upon the stud journal 80 is a cam wing 84 and tensioning this wing is a coiled spring 85 about said stud journal 80, one end being fixed to the commutator switch 81, that is, the rotatable insulator body thereof, and the other end connected to said wing 84 while fixed in the body of the switch 81 is a pin 86 engaged in an arcuate slot 87 formed in said wing 84 and in this manner the said wing 84 when cooperating with the annular flange 88 on the sleeve 31 will have snap action for quick release from the flange 88, the wing 84 being operated for movement of the sleeve 31 reversely to the movement thereof by the cam 46 and thus automatically actuating the toggle switch 66 for opening the circuit through the wires 65 to the motor 30 and thus stopping said motor for rendering the machine passive or inactive. The cam wing 34 rides the flange 88 of the sleeve 31 and two positions thereof being indicated in Figure 6 of the drawings.

The valve 72 has therein a spring 89 for the positive cooperation thereof with the arm 36 of the slide 34.

In the working of the machine, cigarettes 18 in single order will be ejected therefrom, either lighted or unlighted at the option of the operator of the machine and at the same time the said cigarette concurrently with the ejecting thereof will be subjected to an air current for the cleaning of such cigarette to remove dust or impurities therefrom and this air under pressure assures the perfect lighting of the cigarette by the lighter 75 when operating for this purpose. During the lighting operation of the cigarette, those remaining within the magazine 17 are shielded from the smoke of the lighted cigarette during ejecting thereof and also from the possibility of conflagration starting within the machine so that the latter is rendered fireproof.

The full in stroke of the bar 44 after the deposit of a coin 51 within the machine A effects the automatic operation of the machine for the ejecting of a cigarette singly from said machine. Now when the striker 79 is brought to rest for the closing of the switch 78 through a short stroke of the bar 44, the lighter 75 becomes active for the lighting of the cigarette concurrently with the single ejection thereof from the machine.

When the bar 44 has completed its full inward stroke, the circuit to the motor 30 is completed and the latter becomes operative for the automatic working of the machine A. The period of operation for the ejecting of a cigarette from the machine A requires a complete cycle of rotation of the commutator switch 81 and by contact of the striker 79 with the switch 78 on the partial outward stroke of the bar 44 effects the lighting of the cigarette during the ejecting of the same from the machine, being understood, of course, that this switch 78 must be maintained closed for a determined period of time for the lighting operation of said lighter 75.

The transfer of the cigarettes 18 in single order from the magazine 17 to ejecting position in single order is had by the ejector 21 automatically operated in a manner previously set forth.

An additional essential feature of the invention lies in the fact that when the cigarette is being ejected from the machine, it is subjected to a cleaning period when passing through the mouth piece so that the said cigarette is rendered free from impurities and clean in that dust and for-

foreign matter is entirely removed therefrom to avoid contamination when the cigarette is being smoked by a smoker.

What is claimed is:

means actuated by said second-named mechanism for rendering the lighter active and inactive during movements of the slide, means for protecting the contents of the magazine from 5 conflagration during activity of the lighter, manually-actuated means controlling the second-named means, a valved conduit opening through the said lighter for conducting air under pressure therethrough into the path of the cigarette 10 to be lighted, means regulating the valve in said conduit and operated by movements of the slide, a power unit for said second-named mechanism, and means included in the second-named mechanism for regulating the period of activity of the 15 said lighter during the operation of the slide.

9. In a coin-controlled cigarette dispensing and lighting device, a cigarette magazine, a delivery mouth communicating with the magazine, a movable slide communicative with the magazine and the mouth for delivering cigarettes 20 through the latter in single order from the magazine, lighting means movable with the slide for lighting each cigarette during its delivery by said slide through the mouth on activity of the 25 said slide, mechanism supplying air under pressure to the cigarette when lighted and when the slide is delivering such cigarette, mechanism controlling the operation of the slide, means actuated by said second-named mechanism for rendering the lighter active and inactive during 30 movements of the slide, means for protecting the contents of the magazine from conflagration during activity of the lighter, manually-actuated means controlling the second-named means, a 35 valved conduit opening through the said lighter for conducting air under pressure therethrough into the path of the cigarette to be lighted, means regulating the valve in said conduit and operated by movements of the slide, a power unit for said 40 second-named mechanism, means included in the second-named mechanism for regulating the period of activity of the said lighter during the operation of the slide.

10. In a coin-controlled cigarette dispensing 45 and lighting device, a cigarette magazine, a delivery mouth communicating with the magazine, a movable slide communicative with the magazine and the mouth for delivering cigarettes through the latter in single order from the magazine, lighting means movable with the slide for lighting each cigarette during its delivery by said slide through the mouth on activity of the 50

said slide, mechanism supplying air under pressure to the cigarette when lighted and when the slide is delivering such cigarette, mechanism controlling the operation of the slide, means actuated by said second-named mechanism for rendering the lighter active and inactive during movements of the slide, means for protecting the contents of the magazine from conflagration during activity of the lighter, manually-actuated means controlling the second-named means, a valved conduit opening through the said lighter for conducting air under pressure therethrough into the path of the cigarette to be lighted, means regulating the valve in said conduit and operated by movements of the slide, a power unit for said second-named mechanism, means included in the second-named mechanism for regulating the period of activity of the said lighter during the operation of the slide, and said slide including stationary and movable interfitted parts.

11. In a coin-controlled cigarette dispensing and lighting device, a cigarette magazine, a delivery mouth communicating with the magazine, a movable slide communicative with the magazine and the mouth for delivering cigarettes through the latter in single order from the magazine, lighting means movable with the slide for lighting each cigarette during its delivery by said slide through the mouth on activity of the said slide, mechanism supplying air under pressure to the cigarette when lighted and when the slide is delivering such cigarette, mechanism controlling the operation of the slide, means actuated by said second-named mechanism for rendering the lighter active and inactive during movements of the slide, means for protecting the contents of the magazine from conflagration during activity of the lighter, manually-actuated means controlling the second-named means, a valved conduit opening through the said lighter for conducting air under pressure therethrough into the path of the cigarette to be lighted, means regulating the valve in said conduit and operated by movements of the slide, a power unit for said second-named mechanism, means included in the second-named mechanism for regulating the period of activity of the said lighter during the operation of the slide, said slide including stationary and movable interfitted parts, and an air blower included in the air supplying mechanism.

ROBERT L. McCHRISTIAN.
